(No Model.)

J. F. DORNFELD.

CLAY TEMPERING MACHINE.

No. 292,997.

Patented Feb. 5, 1884.

UNITED STATES PATENT OFFICE.

JOHN F. DORNFELD, OF WATERTOWN, WISCONSIN.

CLAY-TEMPERING MACHINE.

SPECIFICATION forming part of Letters Patent No. 292,997, dated February 5, 1884.

Application filed December 10, 1883. (No model.)

To all whom it may concern:

Be it known that I, JOHN F. DORNFELD, a citizen of the United States, residing at Watertown, in the county of Jefferson and State of Wisconsin, have invented certain new and useful Improvements in Clay-Tempering Machines; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

My invention relates to improvements in that class of clay-tempering machines in which a rotating grinding-wheel is attached to a lever or sweep, by which it is caused to roll in a circular course around the clay-pit upon the clay, one end of which sweep is attached to a support at a central point within the circle of the pit, while the other end extends across the pit, and is attached to an endless revolving chain by which it is rotated.

My invention is further explained by reference to the accompanying drawings, in which—

Figure 1 represents a ground plan; Fig. 2, a side view, part in section; and Fig. 3 is a detail.

Heretofore the endless revolving chain A has been supported at intervals around the pit B upon stationary rollers, and motion has been communicated to the sweep or axle C by said endless chain direct, in which case the friction of the endless chain on said stationary rollers caused a great loss of power. By my improvement several sweeps, D and D', are added, all except two of which sweeps are attached to the central platform, E, the inner converging ends of the sweeps D' D' being separated and thrown outward from the center and attached to the next succeeding sweeps in the series, to provide room between them for the clay-tempering wheel F. The sweep C serves as an axle around which the wheel F revolves, and upon which it is free to move toward and from the center back and forth across the pit B, whereby it is caused to traverse over all the clay in the pit. The inner end of the sweep or axle-shaft C is attached to the block G, while its outer end is free to rise and fall, to conform to the movement of the wheel F as

it traverses over the clay. The sweep or axle C and block G are movably secured between the respective sides of the platform E by the horizontal bolt H, which bolt permits said block to move up and down, to conform to the upward and downward movement of the wheel F upon the clay.

It is obvious that the radial sweeps D shown in Fig. 1 support and carry the entire endless drive-chain free from contact with the track, and thus avoid the loss of power heretofore sustained in drawing the chain around the pit upon stationary rollers, said radial sweeps serving the purpose of a large band or sprocket wheel, around which the sprocket-chain A acts as a band, and by which motion is communicated to both the inner and outer ends of the axle C. The outer ends of the several sweeps D and D' are connected together by the brace-rods I. To relieve the platform E from the strain of supporting the outer ends of the sweeps, they are provided with rollers or wheels J, which roll upon the circular track K. Axles L, upon which the wheels J revolve, are rigidly attached at their inner ends to the respective sweeps by bolts or other equivalent means, while to their outer ends are attached brackets or arms M, for supporting the endless chain A.

To the vertical arm of the bracket M is attached a sprocket, N, which is adapted to project through the links of the sprocket-chain, thereby preventing the chain from slipping upon the brackets when communicating motion to the sweeps. In revolving the sweeps and its attachments motion is communicated thereto from the sprocket-wheel O through the endless sprocket-chain A, the chain passing first around the outside of said sprocket-wheel, as indicated by the arrow, then toward the pit, and around the inside of the tightening-wheel P, and from thence to the next bracket, M. The sprocket-wheels O and tightening-wheel P are located outside of the circle described by the ends of the sweeps and brackets far enough to permit them to pass without contact, whereby the line of the draft on the sprocket-chain is drawn as near as possible to the line of motion described by the ends of the sweeps. It is obvious that as each succeeding sweep approaches the sprocket-chain said chain is drawn outward from the sup-

porting-bracket around said sprocket-wheel, and permits one sweep after another to revolve past said wheel. Motion is communicated through the brace-rods I from one sweep 5 to another throughout the series, whereby they all revolve together, like a wheel upon its axis. The platform E is supported upon the central post, R. The motion thus communicated to the series of sweeps through the 10 sprocket-chain A and brace-rods I is transmitted to the axle-shaft C by chain or rod S, as shown, from the next succeeding sweep, D'. The rod S being attached at a fixed point at one end only, the other end is free to rise and 15 fall with the axle-shaft and clay-wheel. The tightener-wheel P is attached to a movable bracket or arm, T, which bracket is pivoted to the frame A' by bolt B', around which bolt it describes a partial circle as it is thrown toward and from the sprocket-chain, said bracket 20 T and tightener-wheel P thereon are drawn toward the sprocket-chain, and said tightener kept in close contact therewith by the gravity of a weight acting through cord C' over sheave 25 D'. The cord C' is attached to a circular arm, E, of said bracket T, by which said cord is caused to at all times act thereon at a uniform distance from the retaining - pivot of the bracket, and with a uniform pressure against 30 said sprocket-chain. Motion may be communicated to said sprocket-chain in any desired manner, either from above through shaft F' or from one side through beveled gear G'. The sprocket-wheel and tightener and the sprock- 35 etts communicated therewith are retained in their proper relative position to each other, as shown; by a substantial frame, and the same is rigidly attached to the side of the pit in the ordinary manner.

40 The inner ends of the several sweeps D are socketed into the platform E, and thus retained by bolts H. The inner ends of the sweeps D' D' are socketed into or otherwise secured to the next succeeding sweeps, D D', as shown. I' I' are braces communicating between the block G and sweeps D' D'.

To facilitate the chain in passing from the brackets M to the sprocket-wheel, the track K is made slightly lower for a small arc of the 50 circle past the sprocket-wheel, as shown in Fig. 3, whereby the sweeps gradually drop below the sprocket-chain as they approach said sprocket-wheel and rise as they recede from it, said wheel thus permitting the chain 55 to move more freely to and from the sprocket-wheel.

Having thus described my invention, what I claim as new, and desire to secure by Letters Patent, is--

60 1. The combination, in a clay - tempering machine, of a central revolving support, a series of radial sweeps, an endless sprocket-chain, an axle-shaft provided with a clay-tempering wheel, and a sprocket-wheel adapted 65 to communicate motion to said chain, said ra-

dial sweeps being provided at their diverging ends with brackets for the reception of said chain, whereby said chain is supported and carried with the sweeps as it communicates motion to them all, substantially as and for the 70 purpose specified.

2. In a clay-tempering machine, the combination of the central support, R, platform E, series of radial arms D and D', brace-rods I, rollers P, endless chain A, circular track K, 75 and sprocket-wheel O, said wheels P being adapted to roll upon the circular track K and support the outer ends of the sweeps, as set forth.

3. The combination, in a clay-tempering machine, of the central platform, E, block G, secured in said platform by horizontal bolt H, radial sweeps D, attached to said platform, sweeps D' D', attached at their inner ends to the next succeeding sweeps, D, axle- 80 shaft C, clay-tempering wheel F, and rod or chain S, said rod S and block G being adapted to communicate a circular motion to said axle-shaft and wheel around the pit, while it permits them to rise and fall, conforming to 85 the height of the clay in the pit, substantially 90 as set forth.

4. In a clay-tempering machine, the combination, with the diverging ends of a series of sweeps centrally supported upon a revolving 95 platform, of the brackets M, axles P, supporting - wheels J, brace-rods I, and sprocket-chain A, said sprocket-chain being adapted to be operated by a sprocket-wheel, around 100 which it passes, and from which it communicates motion to said radial sweeps, said brackets being adapted to support and carry said sprocket-chain, while said brace-rods co-operate to strengthen and sustain said sweeps and communicate motion simultaneously to all, 105 substantially as set forth.

5. The combination, with the endless sprocket-chain A, of the sprocket-wheel O, bracket T, tightening-wheel P, cord or chain C', and sheave D', said cord being provided with a 110 weight adapted to retain said tightening-wheel P in contact with said sprocket-chain, as and for the purpose specified.

6. In a clay-tempering machine, the circular track K, having an arc of its circle next 115 opposite the sprocket drive-wheel depressed or curved downwardly, in combination with the diverging ends of the radial sweeps and their supporting-wheels, said depression being adapted to permit the outward ends of 120 said sweeps with their supporting-wheels to successively drop below said sprocket drive-wheel as they pass it, substantially as and for the purpose specified.

In testimony whereof I affix my signature in 125 presence of two witnesses.

J. F. DORNFELD.
